UNITED STATES PATENT OFFICE.

JOHN H. FOX, OF PITTSBURGH, PENNSYLVANIA, ASSIGNOR TO PITTSBURGH PLATE GLASS COMPANY, A CORPORATION OF PENNSYLVANIA.

GLASS-ROLLING APPARATUS.

Application filed January 17, 1928. Serial No. 247,306.

The invention relates to apparatus for forming glass sheets by a rolling operation, such as that disclosed in the Showers Patent No. 1,579,666, and more particularly to the 5 apron for receiving the glass sheet from the larger of the two rolls. The apron, as heretofore used, consisted of a metal shell having a tapering lip fitting against the surface of the roll at its end and either air or water 10 cooled. In the use of this apron, particularly in the formation of a wide sheet, it was found practically impossible to prevent the apron from bowing up at its center after a period of use, due to the high temperature developed, 15 so that the end or lip of the apron at its center would pull away from the surface of the roll an inch or more, and thus provide an obstruction against the oncoming end of the next sheet of glass over which such edge had 20 to be lifted by the use of hand tools. The present invention is designed to provide an apron constructed to overcome this difficulty, this result being accomplished in part by minimizing the tendency to bow, and in part by 25 providing means whereby force may be applied, tending to resist the tendency of the apron to bow and to force its lip against the surface of the roll. One embodiment of the invention is illustrated in the accompanying 30 drawings, wherein:

Figure 1 is a plan view with the upper sizing roll removed. Fig. 2 is a section on the line II-II of Fig. 1. Figs. 3 and 4 are enlarged detail views of the apron, Fig. 3 being 35 a plan view and Fig. 4 being an end elevation, partially in section. Fig. 5 is a section on the line V-V of Fig. 3.

Referring to the drawings, 1 is the lower sizing roll supported upon the rollers 2 and 40 3, one of which is driven; 4 is the upper sizing roll behind which the body of glass 5 is cast and then formed into the sheet 6 between the rolls; 7 is a suitable framework in front of the roll 1 for supporting the forward end of the runway; 8 is the apron of 45 the runway to which the invention particularly relates; 9 are the rollers constituting a part of the runway to the rear of the apron; and 10 and 11 are a pair of transverse water cooled 50 beams for supporting the apron and runway.

The apron comprises the series of pipes or tubes 13, 14, 15 and 16 surrounded by the sections 17, 17, 17, etc. of sheet metal, the tube 13 being triangular in cross section, while the 55 other tubes 14, 15 and 16 are rectangular in

cross section. These tubes or pipes are preferably made of sheet metal, so that they have a certain degree of flexibility for the purpose, as later explained. They are connected at their ends to the water pipes 18 and 19 (Fig. 60 1), so that they may be cooled by a circulation of water therethrough, the pipes being provided at their ends with valves 20 for regulating the flow.

The sections 17 of sheet metal which surround the pipes are preferably about 12 inches long and are placed end to end, as indicated in Fig. 1, with a slight amount of clearance between the adjacent ends of the sections. The apron is supported by a plurality of levers 21, 21, 21, etc., arranged in series along the length of the apron and secured thereto by means of the bolts 22, as indicated in Figs. 3 to 5. The sections 17 are clamped to the tubes 13, 14, 15 and 16 by means of 70 the bolts 23, preferably located midway between the ends of the levers 21. The levers are fulcrumed upon the transverse water cooled beam 10, this being accomplished by means of bolts 24 which extend through the 75 levers and through suitable brackets 25 (Fig. 4) bolted to the top of the beam 10. The rear end of each of the levers 21 may be adjusted up and down by means of a bolt 26 pivoted at its upper end to a bracket 27 carried upon 80 the lower side of the beam 11. This is accomplished by having the rear end of each lever forked (Fig. 1) so as to fit around a sleeve 28 mounted upon the bolt 26, to which it is pivoted by means of the bolt 29. The 85 sleeve is adjustable up and down by the nuts 30 and 31 threaded onto the bolt 26 on opposite sides of the sleeve.

The frame 7, which carries the beams 10 and 11 is pivotally supported at 33 (Fig. 2) 90 upon the under-framing 34 of the machine, while the front end is adjustable vertically by means of an eccentric 35. This permits the angle of inclination of the runway to be adjusted to meet varying conditions. The 95 frame 7 may be clamped down against the under-framing 34 by any suitable means, the means preferably employed being hooks 36 which are operated by eccentrics 37.

The apron, constructed as illustrated and above described, is relatively flexible and the use of the levers 21 permits the necessary force to be applied to keep the lip 32 (Fig. 5) in close contact with the surface of the roll 1 or closely adjacent thereto throughout 100 110

its length. The making of the casing in the form of the sections 17 reduces the tendency of the apron as a whole to warp. Each section can warp slightly, but the separation of the sections at their ends prevents this warping tendency from being magnified, as would be the case if the casing consisted of a single section extending the length of the water cooled tubes. Any tendency of the sections 10 to warp and pull away from the surface of the roll may be readily counteracted by the independent adjustment of the levers 21, so that additional stress is applied to those portions of the apron which have the greatest 15 tendency to warp and thus pull away from the surface of the roll 1. The flexibility of the pipes or tubes 13, 14, 15 and 16 also contribute to this result, as their tendency to warp is less than that of tubes with heavier 20 walls and the force required by the levers 21 in counteracting this tendency is less than is the case with heavier tubes. By the use of this device, it has been found possible to keep the lip 32 of the apron close to the surface of the roll 1 through a long period of 25 operation, so that the oncoming edges of the successive glass sheets will not catch upon such lip.

What I claim is:

- 30 1. In combination with a glass sizing roll, an apron for receiving the glass therefrom, comprising a tubular member adjacent the surface of the roll, means for circulating a cooling fluid therethrough, a plurality of sheet metal sections, placed end to end, surrounding said member and having tapering lips in opposition to said surface of the roll, and means for supporting said sections.
- 35 2. In combination with a glass sizing roll, an apron for receiving the glass therefrom, comprising a plurality of pipes, placed side by side adjacent the surface of the roll, means for circulating a cooling fluid therethrough, a plurality of sheet metal sections, placed end to end, 40 surrounding said pipes, and having tapering lips in opposition to said surface of the roll, and means for supporting said sections.
- 45 3. In combination with a glass sizing roll, an apron for receiving the glass therefrom, comprising a plurality of pipes of angular cross section, placed side by side adjacent the surface of the roll, means for circulating a cooling fluid therethrough, a plurality of sheet metal sections, placed end to end, 50 surrounding said pipes, and having tapering lips in opposition to said surface of the roll, and means for supporting said sections.
- 55 4. In combination with a glass sizing roll, an apron for receiving the glass therefrom, comprising a plurality of pipes of rectangular cross section, placed side by side adjacent the surface of the roll, means for circulating a cooling fluid therethrough, a plurality of sheet metal sections, placed end to end, surrounding said pipes, and having tapering lips in opposition to said surface of the roll, and means for supporting said sections.
- 60 5. In combination with a glass sizing roll, an apron for receiving the glass therefrom, comprising a tubular member adjacent the surface of the roll, means for circulating a cooling fluid therethrough, a plurality of sheet metal sections, placed end to end, surrounding said member and having tapering lips in opposition to said surface of the roll, and means for supporting said sections.
- 65 6. In combination with a glass sizing roll, an apron for receiving the glass therefrom, comprising a tubular member adjacent the surface of the roll, means for circulating a cooling fluid therethrough, a plurality of sheet metal sections, placed end to end, surrounding said member and having tapering lips in opposition to said surface of the roll, and means for supporting said sections.
- 70 7. In combination with a glass sizing roll, a hollow metal apron of flexible construction at the side of the roll having a tapering lip in opposition to the surface of the roll, means for causing a flow of cooling fluid through the apron, and means for applying force at different points independently along the length of the apron to resist the tendency of the apron to warp and pull its lip away from the surface of the roll.
- 75 8. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 80 9. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 85 10. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 90 11. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 95 12. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 100 13. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 105 14. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 110 15. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 115 16. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.
- 120 17. In combination with a glass sizing roll, a hollow metal apron of flexible construction at the side of the roll having a tapering lip in opposition to the surface of the roll, means for causing a flow of cooling fluid through the apron, a series of levers having their fulcrums fixed against movement and their ends secured to the apron at different points along its length, and means for applying force to the other ends of the levers independently to adjust them, so that the tendency of the apron to warp or bow may be resisted.

In testimony whereof, I have hereunto subscribed my name this 7th day of January, 1928.

JOHN H. FOX.
